UNITED STATES PATENT OFFICE.

IDDO E. CARLSON, OF ELKHART, INDIANA, ASSIGNOR TO C. G. CONN, LTD., OF ELKHART, INDIANA, A CORPORATION OF INDIANA.

HORN VALVE.

Application filed December 12, 1927. Serial No. 239,331.

This invention relates to valved wind musical instruments and especially to horns, cornets, or the like.

In valved wind musical instruments of the 5 horn type it is essential that the reciprocating valve be effectually secured against any rotary movement in the valve casing in order that an efficient registration of the tone openings be effected.

10 The particular object of my invention is to provide a horn valve having an improved key to cause the reciprocating movement of the valve to be in a perfectly straight line.

Another object of my invention is to provide 15 a simple and cheap horn valve key which is readily applied to or removed from the valve.

Other objects of the invention are mentioned and described herein.

20 The preferred embodiment of my invention is illustrated in the accompanying drawing, wherein Figure 1 illustrates a horn valve casing and valve, the former is broken away to disclose my improved key applied to the 25 valve; Fig. 2 is a section taken on line 2-2 of Fig. 1; Fig. 3 is a section taken on line 3-3 of Fig. 1; Fig. 4 is a perspective view of the key alone; Fig. 5 is a perspective view of the top end of the horn valve; and Fig. 30 6 is a perspective view of the top end of the horn valve casing.

Similar numerals of reference indicate like parts throughout the several views on the drawing.

35 Referring to the details of the drawing the numeral 1 indicates a well known type of tubular horn valve casing which is provided with the usual tone connections 2, 2, the latter being shown in fragment. The numeral 40 3 indicates the usual cylindrical valve reciprocally arranged within the casing 1 and adapted for manual actuation by the valve stem 4 which pierces the casing cap 5, the upper end of said stem having the usual finger 45 tip 6 mounted thereon.

The lower end of the stem 4 may be screw threaded into the valve at 7 and may be provided with a shoulder 8 adjacent the upper limit of the screw threads thereon. The 50 numeral 9 indicates the improved valve key 55 body, preferably made of ductile metal, and which may be annular in formation and provided with the integral and marginal key prong 10 bent therefrom at substantially right angles and, depending therefrom when

mounted upon the valve. The key body 9 may be centrally apertured at 11 and is adapted to be secured upon the valve top by the stem shoulder 8 which engages the upper surface thereof when the stem is screwed into 60 position in the valve, and in which position the key prong 10 is arranged partially in the peripheral longitudinal slot 12 formed in the valve 3, and partially in the longitudinal key-way 13 formed in the bore of the 65 valve casing 1, there being sufficient clearance between the key prong 10 and said key-way to enable the operator to freely reciprocate the valve 3.

An important feature of my improved 70 valve key is the ease with which it is applied to or removed from the valve. It is extremely simple, durable and cheap in construction.

From the foregoing description considered in connection with the accompanying drawing it is believed that the construction, manner of use and the various advantages of my invention will be clearly understood. I desire to point out, however, that departure from the structures herein illustrated may be 75 so resorted to within the spirit and scope of my invention as defined in the appended claims.

I claim:

1. The combination with a horn valve casing and a valve reciprocally arranged therein, of means for preventing rotation of the valve within the valve casing, said means including registering longitudinal grooves formed in the valve outer periphery and the valve casing bore, and an elongated tongue 90 engaging both of said grooves.

2. The combination with a horn valve casing and a valve reciprocally arranged therein, of key means for preventing rotation of the valve within the casing, said key means 95 including registering longitudinal grooves formed in the valve outer periphery and the valve casing bore, said valve groove extending through the end thereof, and an elongated tongue mounted in said valve groove and engaging said valve casing groove.

3. The combination with a horn valve casing and a valve reciprocally arranged therein, of an elongated tongue and groove connection between the valve and valve casing 105 adapted to prevent rotation of the former within the latter, a valve stem, and means connecting the valve stem and said tongue for securing the latter to said valve.

4. The combination with a horn valve cas-

110

ing and a valve reciprocally arranged therein, of a tongue and groove connection between the valve and valve casing adapted to prevent rotation of said valve within the casing, 5 said tongue being provided with a lateral projection, and a valve stem mounted upon said valve and engaging said tongue lateral projection to fasten the tongue in position.

5. In combination, a horn valve casing, a 10 valve reciprocally arranged therein, a tongue and groove connection between said valve and

casing to prevent rotation of the former, said tongue being provided with an apertured lateral projection arranged upon the valve top end, and a valve stem threaded into said valve 15 through the aperture in said tongue lateral projection and engaging the latter to fasten said tongue in position.

In witness whereof I have hereunto affixed my signature this 9th day of December, 1927.

IDDO E. CARLSON.
